UNITED STATES PATENT OFFICE.

WALTER J. COCHRAN, OF SOUTHBORO, MASSACHUSETTS.

CLUTCH.

No. 829,140.

Specification of Letters Patent.

Patented Aug. 21, 1906.

Application filed September 16, 1906. Serial No. 278,703.

To all whom it may concern:

Be it known that I, WALTER J. COCHRAN, a citizen of the United States, and a resident of Southboro, in the county of Worcester and State of Massachusetts, have invented new and useful Improvements in Clutches, of which the following is a specification.

My invention relates to clutches, and has for its object the provision of a powerful, reliable, durable, and easily-operable clutch which is especially adapted to situations which require an interrupted or intermittent transmission of power, such as presented, for instance, by motor-cars.

In the drawings forming a part of this specification and illustrating one embodiment of my invention and improvements, Figure 1 is an elevation of the clutch and its operating mechanism, partly in section, on the line 1 1 of Fig. 2. Fig. 2 is a side elevation of the clutch and its operating mechanism. Fig. 3 is a longitudinal section of the clutch on line 3 3 of Fig. 1. Fig. 4 is a section of a detail following line 4 4 of Fig. 1, the scale being enlarged; and Fig. 5 is a detail of one of the clutch-operating levers, also on a scale larger than that employed in Figs. 1 to 3, inclusive.

The clutch itself comprises two relatively movable clutch members preferably in the form of the clutch-rings D' and R, whereof D' is secured to a disk or wheel D, the same being keyed to the inner shafts. The clutch-rings D' and R are shown as provided with opposing conical surfaces interengagement of which is secured by the relative longitudinal movement of the two clutch-rings.

S' is a sleeve loosely mounted upon the inner shaft S, so as to permit the latter to turn independently of sleeve S', except when the clutch is set. Upon sleeve S' there is formed integral with or otherwise secured to said sleeve a frame S², said frame in the illustration shown consisting of a four-armed spider, whereof the arms S² are stiffened by webs S³ and provided with posts S⁴ for the reception of the pivot-pins s. The spider-frame S² is provided with a sliding connection with the clutch-ring R, this sliding connection consisting of the pins P, each of which is secured at the end of one of the spider-arms and each of which passes through a hole in a lug R⁴, which is integral with or otherwise secured to the clutch-ring R'. Springs P', which surround said pins P, are placed between the spider-arms S² and the lugs R⁴. Thus the spider-frame S² must partake of any rotary move-

ment of the clutch-ring R, and the clutch-ring R is caused to slide upon the pins P in one direction under the influence of the springs P' and in the other direction under the influence of the controlling mechanism.

Levers L are pivoted upon the pins s. These levers bear at their outer ends upon the shoes R⁵, which are mounted upon base-blocks R², attached to the ring R. The inner ends of these levers bear tangentially upon the sliding cone C, which acts as a wedge in the manner presently to be described. The levers each terminate at their inner ends in a reduced portion or pivot L', whereon are mounted antifriction rollers or balls L', and at their outer ends with similar pivots L², whereon are mounted the antifriction-rollers L². (See particularly Fig. 5.) An additional bearing or support is provided for the levers L, which consists of the ring K, made integral with or otherwise secured to the spider-arms S².

The cone C is mounted to slide upon the shaft or sleeve S' and is operated by means of a ring or yoke Y, which is placed in groove C² and is actuated by an operating-lever H through the links and levers H⁴, H³, and H². The lever H³ is pivoted at H⁵, and the lever H is pivoted at H⁶. These pivotal connections may be secured to or mounted on any fixed object or part of the machine-frame.

In Fig. 4 the construction of the clutch-operating inclines is shown in detail. Upon the clutch-ring R there is a base-block R², the upper surface of which is preferably inclined and is serrated or corrugated, as at r'. The block is slotted at R⁸ R⁸. The bearing-shoe or incline proper, R³, has a lower surface inclined to correspond with the upper surface of the base-block R² and is also serrated or corrugated, as at r, to correspond with the upper surface of said base-block. The shoe R³ is bored to receive the screws R⁹ R⁹, which pass through the slots R⁸ and are threaded into holes in the clutch-ring R. The shoe R³ is provided with an inclined bearing-surface R⁴ for the ends of the levers L and with a level surface or terminal dwell R⁵. By shifting the base-block R² to the right or left, as shown in Fig. 4, under the shoe and resetting the screws R⁹ a nice adjustment can be secured to insure the proper setting of the clutch. In like manner wear also may be taken up when occasion requires.

The operation of the clutch is as follows: Upon shifting the cone C inwardly or to the

left, as shown in Fig. 3, by swinging the lever-handle H the rolls L' of the levers L are caused to ride up on the surface of the cone C, which acts as a wedge. The levers are thus turned upon their pivot-pins s, and the outer ends of the levers—namely, the rollers L², as shown in the drawings—are caused to ride up on the inclined surfaces R⁴ of the shoes R³ overcoming the resistance of springs P and forcing the clutch-ring R into frictional engagement with the clutch-ring D' and binding the conical surfaces R' and D' firmly together. The bearing-ring K upon the spider-arms S² offsets any tendency of the levers L to be sprung or bent during the operation of the clutch-setting. The clutch, however, will be found to work admirably without the bearing-ring K if the levers and their pivotal connections with the spider-arms are sufficiently strong and rigid. When the clutch is fully set, the rolls L' at the inner ends of the levers slip into the groove C' of the cone C, causing the clutch members to be held in engagement until the cone is again pulled back by the operating-lever H. The rolls L² at the same time will rest upon the level surfaces or dwells R⁵ of the shoes R³, thus obviating any tendency of the clutch-ring R² to be urged away from the clutch member D', which would result were the shoe R³ provided with a continuously-inclined surface. When the clutch is in its withdrawn position, as shown in Fig. 3, the rolls L' bear upon the short cylindrical collar or lip C³ at the end of cone C. In disengaging the clutch members the handle or lever H is thrown back sufficiently to move the groove C' out of engagement with the rollers L' at the ends of the levers, whereupon the springs P' operate to throw the clutch-ring R into normal inoperative position, as shown in Fig. 3. A suitable relation between the fulcrum, power, and load of the levers is illustrated in the accompanying drawings. It will be obvious, however, that by moving the fulcrums of the levers near the outer ends—that is, nearer the load—a clutch of very great power may be provided. Springs Q may be provided, secured at one end to the ring R and at the other end to the levers L by suitable pins or posts, as shown, or in any convenient manner. The springs Q tend to pull the levers toward their inoperative position and assist in releasing or disengaging the clutch members when the rollers L' have been dislodged from the groove C'.

I claim—

1. In a clutch, the combination of a pair of relatively movable clutch members one of which is provided with inclined bearings, and means to engage said clutch members comprising a movable wedge, levers bearing at one end on said wedge tangentially, and at the other end upon said inclined bearings and means to move the wedge.

2. In a clutch, a pair of relatively movable clutch-rings one of which is provided with inclined bearings, and means to engage the rings, comprising a movable cone mounted to slide parallel to the axis of the rings, a frame, levers pivoted to the frame, sliding connections between the frame and one of the clutch-rings, said levers bearing at one end tangentially on said movable cone, and at the other end upon said inclined bearings, and means to move the cone. 70

3. In a clutch, a pair of relatively movable clutch-rings one of which is provided with inclined bearings, and means to engage the rings, comprising a movable cone mounted to slide parallel to the axis of the rings, a frame, levers pivoted to the frame, sliding connections and releasing-springs between said frame and one of the clutch-rings, said levers bearing at one end tangentially on said movable cone, and at the other end upon said inclined bearings, and means to move the cone. 80

4. In a clutch, a pair of relatively movable clutch-rings, a shaft to which one of the clutch-rings is secured, a sleeve on said shaft, a frame secured to the sleeve, a cone mounted to slide on the sleeve, levers pivoted to the frame, sliding connections between the frame and one of the clutch-rings inclined bearings upon the sliding clutch-ring, said levers bearing at one end tangentially upon the cone, and at the other end upon said inclined bearings, and means to move the cone. 95

5. In a clutch, a pair of relatively movable clutch-rings, a shaft to which one of the clutch-rings is secured, a sleeve on said shaft, a frame secured to the sleeve, a cone mounted to slide on the sleeve, levers pivoted to the frame, sliding connections and releasing-springs between the frame and one of the clutch-rings, inclined bearings upon the sliding clutch-ring, said levers bearing at one end tangentially upon the cone, and at the other end upon said inclined bearings, and means to move the cone. 100

6. In a clutch, a pair of relatively movable clutch-rings, a shaft to which one of the clutch-rings is secured, a sleeve on said shaft, a frame secured to the sleeve, a cone mounted to slide upon the sleeve, levers pivoted to the frame, a supporting-bearing on the frame to prevent the levers from being bent or sprung out of their plane of oscillation, sliding connections between the frame and one of the clutch-rings, inclined bearings upon the sliding clutch-ring, said levers bearing at one end tangentially upon the cone, and at the other end upon said inclined bearings, and means to slide the cone. 115

7. In a clutch, a pair of relatively movable clutch members one of which is provided with inclined bearings, and means to engage the clutch members, comprising a movable wedge mounted to slide parallel to the axis of the clutch members, levers bearing at one 120

- end on said wedge and at the other end upon said inclined bearings, antifriction-rollers at the ends of said levers, and means to move the wedge.
5. 8. In a clutch, a pair of relatively movable clutch members one of which is provided with inclined bearings, and means to engage the clutch members, comprising a movable wedge mounted to slide parallel to the axis of the clutch members, levers bearing at one end on said wedge and at the other end upon said inclined bearings said inclined bearings having terminal dwell-surfaces upon which the outer ends of the levers rest when the clutch is set.
15. 9. In a clutch, a pair of relatively movable clutch members adjustable bearing-shoes upon one of said clutch members having inclined surfaces, and means to engage the clutch members, comprising a movable wedge mounted to slide parallel to the axis of the clutch members, levers bearing at one end on said wedge and at the other end upon the inclined surfaces of said bearing-shoes, and means to move the wedge.
20. 10. In a clutch a pair of relatively movable clutch members, bearing-shoes secured to one of said clutch members having inclined bearing-surfaces, means to adjust the bearing-shoes comprising shiftable base-blocks interposed between the bearing-shoes and the clutch member, and means to engage the clutch members comprising a movable wedge mounted to slide parallel to the axis of the
- clutch members, and levers bearing at one end on said wedge and at the other end on said bearing-shoes.
11. In a clutch, the combination of a pair of relatively movable clutch-rings one of which is provided with inclined bearings, and means to engage said rings comprising a movable wedge, a lever-support, levers mounted thereon to swing in a plane perpendicular to the clutch-axis and bearing at one end upon said wedge and at the other end upon said inclined bearings, and means to move the wedge.
40. 12. In a clutch, a pair of relatively movable clutch-rings, a shaft to which one of said rings is secured, a sleeve on said shaft, a frame secured to the sleeve, a cone mounted to slide on the sleeve, levers pivoted to the frame and swinging in a plane perpendicular to the clutch-axis, sliding connections between the frame and one of the clutch-rings, 45 adjustable bearing-shoes secured to the sliding ring having inclined bearing-surfaces, said levers bearing at one end tangentially upon the cone and at the other end upon said bearing-shoes, antifriction-rollers at the ends 50 of said levers, and means to slide the cone.
